UNITED STATES PATENT OFFICE.

LOUIS H. HOOVER, OF ST. LOUIS, MISSOURI.

TACK-HAMMER.

SPECIFICATION forming part of Letters Patent No. 392,515, dated November 6, 1888.

Application filed February 4, 1888. Serial No. 263,037. (No model.)

To all whom it may concern:

Be it known that I, LOUIS H. HOOVER, of St. Louis, Missouri, have made a new and useful Improvement in Tack-Hammers, of 5 which the following is a full, clear, and exact description.

The improvement relates to that class of tack-hammers in which the tack can be held in the hammer-head in entering the tack into 10 the surface into which it is being nailed; and it consists in the special means for holding the tack, substantially as is hereinafter described and claimed, and as illustrated in the annexed drawings, making part of this specification, in 15 which—

Figure 1 is a view in perspective of the improved tack-hammer; Fig. 2, an end elevation of the hammer; Fig. 3, a plan of that face of the hammer-head in which the tack is held; 20 Fig. 4, a section on the line 4-4 of Fig. 2; Fig. 5, an elevation of the hammer-head looking at the opposite side to that presented in Fig. 2; and Fig. 6 is a vertical section on the line 6-6 of Fig. 5. In Figs. 2 and 4 a tack is shown 25 attached to the hammer as in use.

The same letters of reference denote the same parts.

Saving as it may be modified by the embodiment therein of the present improvement, the 30 hammer A is of any of the customary forms. In the hammer-head a, just within and parallel substantially with the face a' of the hammer-head, is a recess, B. It extends well across the hammer-head, and at b it is open to receive the tack C, and also to admit of the insertion of the spring D, which, in conjunction with the recessed hammer-head, constitutes the means for holding the tack. The face a' is slit at a'', the slit being extended in the direction of the recess B, and being open at a'' to admit the tack. The spring is composed of a piece of wire bent into the shape shown substantially in Fig. 4—that is, the wire is folded at its middle d, and at that point it is held in 40 an offset or niche, b', at the inner end of the recess B, and from that point the two parts

d' d' of the spring extend toward the open end b of the recess, and as they approach the end b the parts d' d' open from each other to enable the tack to readily enter between them, and after thus opening apart the parts d' d' are folded and returned into the recess to enable the ends d' d' of the wire to press against the sides b b, respectively, of the recess B, and thereby both hold the spring better in place 55 and provide for better holding the tack in the hammer. The spring D, as indicated in Fig. 6, is also preferably so made as to incline its outer portion toward the face a' of the hammer-head. 60

The mode of holding the tack in the hammer is obvious, by reference to Figs. 2 and 4. The insertion of the tack is facilitated by the groove a' which leads to the recess. The tack-head enters the groove and slides therein until 65 it encounters the outer end of the spring D, when it is moved inward into the spring and recess, as shown. After the point of the tack has been inserted in the surface into which it is to be nailed, the hammer is slipped from off 70 the tack and the driving of the tack is completed in the usual manner. It will be observed that the spring D does not extend outward beyond the face a', and that the hammer-head is free of all projections. It will also be 75 noticed that the spring D is adapted to tacks of various sizes, and it is in this respect that the present construction is an improvement upon that patented to me June 21, 1887, numbered 365,255, and 80

What I claim is—

The combination of the hammer-head and the spring, said head being recessed and having its face slit, as described, and said spring being doubled and held at its middle, at the 85 inner end of the recess, and having its parts folded to enable the spring to hold tacks of different sizes, substantially as described.

LOUIS H. HOOVER.
